PLOW COUPLING

Tracy L. Fields, Wasco, Oreg.

Application June 24, 1937, Serial No. 150,194
Renewed December 30, 1938

1 Claim. (Cl. 97—77)

My invention relates to improvements in couplings for disk plows and the primary object thereof is to provide a practical, inexpensive and reliable coupling for securing two disk plows together in end to end relation.

Another object is to provide a device of the character and for the purpose above set forth which may be readily attached and used on standard types of disk plows without necessitating expensive alteration in the standard construction of such plows.

To the accomplishment of the above, and subordinate objects presently appearing, a preferred embodiment of my invention has been illustrated in the accompanying drawings, set forth in detail in the following description and defined in the claim appended hereto.

In said drawings:

Figure 1 is a fragmentary view in perspective of two disk plows coupled together by means of my improved coupling.

Figure 2 is a fragmentary view in top plan illustrating a link, forming part of my improved coupling, and the manner in which it is attached to the gang frame of a plow.

Figure 3 is a view in transverse section taken on the line 3—3 of Figure 2, and

Figure 4 is a similar view taken on the line 4—4 of Figure 2.

Referring to the drawings by numerals, 1 and 2 designate opposite end portions of two disk plows, respectively, of a well known type coupled together end to end. These plows being well understood in the art need merely be briefly described herein. Such plows include a gang frame 3 comprising a pair of laterally spaced front and rear bars, as at 4 and 5, secured together by cross bars as at 6. The disks 7 are mounted on the rear frame bar 5 to trail therefrom and by means of a shaft 8 mounted in bracket arms, one of which is shown at 9, extending from said bar. At the rear end of each plow is a furrow wheel 10 of the usual type, a function of which, as is well known, is to adjust the depth of the furrows formed and which for this purpose is mounted on a vertical shaft-like support 11 slidable and rotatable in a casting 12 secured to the rear end of the gang frame 3 in a manner well understood and therefore not illustrated in the drawings. The numeral 13 designates a part of means for securing the casting 12 to the frame 3 and 14 and 15 a bolt and bolt holes, respectively, in said casting and part for adjustably securing the casting to said part 13. The depth of the furrows is regulated

by adjusting the casting 12 vertically on the support 11 and hence adjusting the frame 3 vertically. Part of the mechanism for adjusting the casting 12 has been indicated at 16 but such mechanism being well known need merely be identified in passing. According to my invention, the casting 12 is formed with a lateral extension 17 bifurcated to provide vertically spaced ears 18 forming part of a coupling the other element of which is a bar like link 19 one end of which is pivoted between said ears 18 by means of a vertically disposed headed coupling pin 20 passing through said ears and end. A cotter pin 21 secures the coupling pin 20 in proper position. The other end of the link 19 is connected to the front end of the other plow 2 so that said plow is pulled by said link to trail behind plow 1 to which said link is pivoted. Preferably the link 19 is connected to the trailing plow 2 between the bars 4 and 5 thereof by bolting said link intermediate its ends, as at 22, on one of the cross bars 6 usually disposed at the front end of the frame 3. The end of the link 19 opposite the pivoted end thereof is similarly secured, as at 23, down onto a cross bar 24 bolted, as at 25, to the frame bars 4 and 5. A similar bar 26 is bolted, as at 27, to the frame bars 4 and 5 to extend over the link 19 on the opposite side of the bolt 22. The described relation of the bars 24 and 26 and the link 19 provides a strong connection for lifting the front end of the trailing plow 2 by the rear end of the leading plow 1 when the latter is adjusted upwardly. The described pivoted coupling provides, as will be clear, for turning of the plows either to the right or left without crowding one or the other and eliminates side draft. The space between the ears 18 is designed to provide a clearance for the pivoted end of the link 19 and the pivotal connection of the link 19 to the coupling bar 20 is loose so that said link may swing up and down on said pin between the ears 18 and thereby permit relative vertical movement of the plows 1 and 2 as for instance on uneven ground.

The invention, it is believed, will be clear from the foregoing without further explanation.

Manifestly my invention, as described, is susceptible of modification without departing from the inventive concept and right is herein reserved to all such modifications falling within the scope of the claim appended hereto.

What I claim is:

The combination with a pair of disk plows each including a gang frame having a pair of front and rear side bars and one having a rear end

furrow wheel and a vertical support therefor, of means for coupling said plows together end to end and including a bifurcated casting secured to the rear end of the frame of said one plow and vertically adjustable on said support to correspondingly adjust said one frame, a coupling bar pivotally connected at one end in the furcations of said casting, and means to rigidly connect the other end of the coupling bar to the

front end of the other plow comprising a pair of superposed plates secured at their ends to the front and rear frame bars of said other plow and receiving said coupling bar therebetween, and a third plate in the rear of said pair secured at its ends to said frame bars and having the other end of the coupling bar fixed thereon. 5
